CLAIM

The ornamental design for a display panel of a programmed computer system with graphical user interface, as shown and described.

DESCRIPTION

FIG. 1 is a front view of my computer monitor display with graphical user interface showing my new design; FIG. 2 is another front view thereof.

FIG. 3 is another front view thereof.

FIG. 4 is another front view thereof.

FIG. 5 is another front view thereof.

FIG. 6 is another front view thereof.

FIG. 7 is another front view thereof.

FIG. 8 is another front view thereof.

FIG. 9 is another front view thereof.

FIG. 10 is another front view thereof.

FIG. 11 is another front view thereof.

FIG. 12 is another front view thereof.

FIG. 13 is another front view thereof.

FIG. 14 is another front view thereof.

FIG. 15 is another front view thereof.

FIG. 16 is another front view thereof; and,

FIG. 17 is another front view thereof.

The perimeters of the portion of the underlying portion of a computer monitor display and the graphical user interface are understood to be flush.
